[57] CLAIM

The ornamental design for a beverage container, as shown and described.

DESCRIPTION

FIG. 1 is a perspective view of a beverage container showing our new design;

FIG. 2 is a top plan view thereof;

FIG. 3 is a side elevational view thereof;

FIG. 4 is a bottom plan view thereof;

FIG. 5 is a vertical cross-sectional view thereof; and

FIG. 6 is a fragmentary, enlarged view taken on the line 6—6 of FIG. 2.

FIG. 1.FIG. 2.FIG. 3.FIG. 4.FIG. 5.FIG. 6.
